CENTRIFUGAL RING-INGOT CASTING
MACHINE

James L. Adams, Jr., Youngstown, Ohio

Application July 15, 1933, Serial No. 680,570

12 Claims. (Cl. 22—65)

The present invention relates broadly to the art of ingot casting, and more particularly to the high-speed centrifugal casting and jarring of relatively much wider axially, and thinner radially, than usual, circular metal ingots, together with continued control of the initial cooling and solidification thereof, in such wise as to give very great compactness to the mass, and uniformity of composition to the metal, with substantially complete absence of the customary pipes, pockets, and other central or sub-surface cavities, along with substantial elimination of a great part of the usual occluded and trapped gases, and detrimentally located dendritidal crystals, all these improvements leading to the production of a greater uniformity of both constitution and texture of the metal mass, than is the case in the usual ingot of commerce, where considerable segregation, or separation-out of the several constituents of the mix, normally occurs during the initial cooling and solidification period.

My present invention also includes closely coordinated means for quickly hot-cleaning, or hot-trimming lightly, certain surface elements of the ingot, very closely after initial solidification, and while the metal is still very plastic, in order to substantially eliminate certain surface inclusions, and the better prepare the entire ingot for subsequent belt-mill rolling, as by my mill covered by co-pending application Serial No. 674,661, filed June 7th, 1933.

Some six of the primary objects of the present invention, therefore, consist in the provision of rugged apparatus for the ultra-rapid production at low cost of substantially circular ring-ingots, which are (1st) highly compacted, (2nd) of very uniform composition throughout, (3rd) substantially pipe-less and gas free, (4th) of extra wide and thin type, (5th) of metal which has been repeatedly jarred during its solidification, and (6th) which are of such form as to be readily white-hot brushed, or skim-trimmed by circular, rotating blade cutters, if desired, previous to the rolling operation.

Another important object is to provide apparatus which will give progressive solidification from one broad face of the ingot toward the other, along its thinnest or radial dimension, and not from each of the four main outside surfaces inward, toward the centre of the section, since in this latter process the progressive multi-directional shrinkage of the metal as it solidifies and cools, leads directly to the necessary concomitant formation of interior pockets, fissures, pipes,

and cracks, all contributing numerous causes for waste, and high costs of rolling.

A vital object is to greatly cut these plate and sheet manufacturing costs, by providing apparatus for the production of a type of ingot eminently suited for use in connection with a high-speed and high-capacity, continuous belt-mill, such as that disclosed in my co-pending application previously referred to.

Another essential object is to provide a means for the high-speed, low-cost, quantity production of centrifugally-cast, jarred, and trimmed ring-ingots, of ultra-low porosity, and high uniformity of texture and composition.

One leading object is to substantially wipe-out the usual 10% to 15% end-crop loss, common to the customary straight types of ingot, and thus cut final plate costs.

Another object is to greatly cut the usual initial solidification time, as well as the length of the soaking-pit period, by casting in much thinner sections than has been customary heretofore in ingots for rolling mill use.

A still further object is to provide for the production of a ring ingot, which can be slowly rotated on its axis, if desired, during gas, oil, powdered coal, induction electric, or other heating, so as to make doubly sure of the uniformity of the heating therearound.

Another outstanding object is to provide an ingot of such form that it will require a minimum number of passes in the mill to convert into plate, or moderately thin sheet, so as to thereby greatly conserve the total rolling mill time, increase the tonnage output, and decrease the conversion costs into such products.

One noteworthy object is to so fore-shorten the solidification time, by reducing the maximum section thickness found in the ingot, as to materially lower the time allotted for segregation of the materials of the mix, and also the period allowed for growth of the metal crystals, thus leading not only to a more general uniformity of the material throughout the casting, but to a smaller and more refined grain structure throughout the ingot, as it leaves the casting unit.

An added object is to produce a centrifugal casting machine, or unit, in which the casting occurs with a minimum of splashing of the entering metal.

A supplementary object is to provide means for the production of an ingot which can be conveniently hot-trimmed either by high-speed wire-brush means operating on the white hot and still slightly plastic material, or by water-cooled ro-

tary blade trimmers functioning at a slightly later stage in the cooling.

Other worthwhile objects will be obvious to anyone versed in the art to which this invention appertains.

With all these and other objects in view, I have provided an apparatus for the high-speed centrifugal casting and shaking of axially wide and radially thin ring-ingots, of substantially compact metal, and uniform texture throughout.

It will be noted that my apparatus provides for keeping the interior broad face of the ingot liquid, or plastic, as long as may be required to assure that the solidification will be progressive from the outer peripheral face only, and thence inward through the casting toward central axis, and under such centrifugal and jarring conditions as will assure a maximum of compacting of the metal, but without unduly extending the period of such solidification so as to permit the growth of large crystals in the metal, and extensive segregation of the more easily crystallized elements of the initial composite mix.

It will be further noted that my apparatus provides for the white-hot brushing, or the light hot-trimming of the interior face of the newly formed ingot, or for both of these operations in sequence, so as to substantially eliminate interior surface inclusions, centrifugally separated materials, and excessive thickness variations in spots around the periphery, all of which would be detrimental to final rolled product. It is conceivable, however, that such surfacing operations on the ingot might be dispensed with in some cases, as where utmost cleanliness of metal is non-important, or slight defects in the rolled plate are not material.

In the drawings, Figure 1 shows a plan view of my complete apparatus, except as broken away to illustrate at Figure 1A a portion of my rotating track disc, and as further broken away at Figure 1B to show a typical radial segment of the lower stationary track mounted upon concrete or other base, in a shallow pit below.

The approximate position of the various operating stations are indicated hereon, it being noted, however, that the hot-brushing station will usually be located one or two positions further to the left, and the stripping station a little higher up on the right, so as to provide a little more distance to the pouring station in each case.

Figure 2 is a vertical section taken on line II-II of Figure 1, looking with the arrows, except as partly broken away, and shows the ultra simplicity of the method of drive utilized for the centrifugal action, this drive being common to all of the 30 moulds shown on previous figure.

Figure 3 is an enlargement of section III-III of Figure 1, to better bring out some of the features of construction, and is also a plan view.

Figure 4 is, similarly, an enlargement of Figure 2, and indicates the lines on which Figures 1A and 1B, above, are taken, looking with the arrows.

Figure 5 is a plan view, enlarged, of the segment V-V of Figure 1, covering the pouring station.

Figure 6 is an elevation of the scale-beam element shown at top of Figure 5, taken as per line VI-VI, and looking in the direction of the arrows. In actual practice, of course, this scale-beam would be located very considerably farther away from the hot-metal ladle than is here shown, and with appropriate hot-metal protection there between.

Figure 7 is an elevation and partial section of

the apparatus shown on Figure 5, taken about on the line VII-VII of latter figure, again looking with the arrows.

Figure 8 is a part section of pouring-cone, taken on the line VIII-VIII of Figure 7, looking with the arrows, but somewhat enlarged to show the ribs more clearly.

Figures 9 and 10 show in succession the roller mounting means provided for pouring-cone support, and successive sections of said pouring-cone, taken on the appropriately numbered lines of Figure 7, again looking with the arrows.

Figure 11 illustrates an enlarged plan view, partly in section, of the hot-brushing station elements positioned at about XI-XI, or somewhat further to the left, in Figure 1, along the positioning rail indicated.

Figure 12 shows this hot-brushing station in partial elevation and part section, about as per line XII-XII of Figure 11, again with the arrows.

Figure 13 is a partial section of the parts of Figure 11, as per line XIII-XIII thereon. Figure 14 is a partial elevation, showing certain elements of Figure 12, as taken from line XIV-XIV on this latter figure, and with connecting-rod in section.

Figure 15 is an enlargement of hot-trimming station apparatus, in plan view, and covering certain elements shown at about the position XV-XV around the circle of Figure 1, but with the casting mould removed, and one trimmer shown in section.

Figure 16 is a vertical section, shown partially in elevation, of the parts of Figure 15, taken on the line XVI-XVI of latter, more or less, but with casting mould and contained ring-ingot added in order to show the relation of the parts. The screw-down section is taken, per force, a little nearer the vertical axis.

Figure 17 is a section of casting mould, with its contained ingot, taken on line XVII-XVII of Figure 16, with the arrows.

Figure 18 is a part section and part elevation of the trimmer mechanism, taken on the appropriately numbered line of Figure 16.

Figure 19 is a section of trimmer-head-adjusting drive only, per line XIX-XIX of Figure 16. This adjustment is necessary to take care of slightly coned ingots.

Figure 20 is a transverse vertical cross-section on line XX-XX of Figure 16, while Figures 21 and 22 are further transverse cross-sectional views of trimmer parts, as per the appropriately numbered arrows on Figure 16.

Figure 23 is an enlargement, likewise in section, of parts near the XXII-XXII line on Figure 16, but looking in same direction as latter figure, while

Figures 24 and 25 show the appropriately marked sections taken on the lines indicated in Figure 23, with the arrows.

Figure 26, on next sheet of drawings, illustrates an enlarged plan view of the apparatus forming the step-by-step indexing station, as indicated at XXVI-XXVI position, and external to the largest circle of Figure 1, the latter figure showing, however, certain of the casting wheel parts which were broken away in Figure 1, and in addition appropriate connections for the driving motor, including necessary contactors and limit switches designed to give the step-by-step motion required, although other equivalent means for accomplishing this result might easily be cited.

Figures 27A and 27B illustrate top and bottom ½-sections, respectively, of a casting mould to

produce slightly tapered, and parallel sided ring-
ingots, respectively, these mould sections being
in general similar to such parts as shown on Fig-
ures 11 and 12, but considerably enlarged, and
5 taken axially of the ingot.

The mould-head proportions shown in the
earlier figures indicate preferred constructions,
however, the later figures being foreshortened
here due to space limitations. Figure 27B also
10 shows a portion of the trackway, and its support-
ing driven disc, as well as a limit outline, in dotted
lines, of the ingot-jarring cam, below and to the
left, adjacent the section of track.

Figure 28 shows an enlarged plan view of ingot-
15 stripping station, as indicated at about the position
XXVIII—XXVIII on Figure 1, but with ingot
receiving parts of ingot-carriage, such as that
disclosed in my co-pending application Serial No.
652,142, filed January 17th, 1933, for example,
20 shown in dotted outline to the left.

Figure 29 is a vertical section of this ingot-
stripping-apparatus, taken on the axis of Figure
28, and again looking with the arrows.

Figure 30 is an end elevation of certain ingot-
25 stripper parts of Figure 29, as identified by the
line XXX—XXX and arrows, on latter figure.

Figure 31 is a similar left end elevation, taken
further to the left, as per line XXXI—XXXI and
30 arrows, and shows the action of ingot-lifting
rig on ingot-carriage, in dotted outlines, and as
already referred to in connection with Figure 28.

Figure 32 shows in section the ingot-stripper
drive, for "starting" the tapered ingot from the
mould, while the latter is still, or is under full-
35 speed rotation, and shifting it over to the dotted
outline position within the mould, as shown in
Figure 29, on which figure the line of section
XXXII—XXXII is indicated also.

Figure 33 is a section of stripper arms taken
40 on line XXXIII—XXXIII of Figure 29.

Figure 34, on succeeding sheet of drawings, illus-
trates in plan view a complete casting room
and rolling mill assembly utilizing my improved
45 centrifugal casting unit, and also indicating be-
low, two of my circular ingot heating, or tempera-
ture equalizing furnaces, as disclosed in co-pend-
ing application, Serial No. 655,185, filed February
4th, 1933.

Figure 35 shows in elevation certain ingot-jar-
50 ring elements taken from Figure 7, so as to illus-
trate them in proper relation to the succeeding
figure.

Figure 36 shows in section these ingot-jarring
55 devices, and also, in more detail than heretofore,
a cross section of a preferred form of ingot mould,
all taken on the broken line XXXVI—XXXVI of
Figure 35, in the direction of the arrows.

Figure 37 indicates a horizontal section and part
60 plan view, taken on the line XXXVII—XXVII
of Figure 35, and showing the means provided
for eccentric bushing adjustment, whereby the
amount of jarring at this station is controlled,
or eliminated entirely, as desired. It will be un-
derstood that as many of these jar-control sta-
65 tions as required, will be installed in succession,
up to the point of final ingot solidification only,
and that the casting-wheel indexing rig will stop
the wheel successively upon these jarring station
positions. It will be further noted that the
70 gradual rise of the ingot mould is taken care of
by these lifting wheels, but that the impact from
the drop of said mould is taken by the moving
track and disc-wheel, and not by the relatively
light bearings of the lifting rig, since on its drop
75 the mould clears the latter slightly. If the lift-

ing wheel is thrown down by moving the eccentric
bushing in which it is mounted, the lifting cam
on rotating mould will be entirely cleared, so that
no more jarring occurs.

Figure 38 shows in plan an alternative form of
centrifugal casting and jarring unit, Figure 38A a
segment of the rotating disc, and Figure 38B the
underlying stationary track thereof, the various
station positions being indicated as before.

Figure 39 is a vertical section, taken on the 10
broken line XXXIX—XXXIX of Figure 38, show-
ing this reduced size casting wheel, in which the
rotation of ingot is maintained only through the
solidification period, and not all through the
period of cooling, as was done in the machine 15
first shown and described.

Figure 40 is a plan view of the second-stage
wheel, and Figure 40A of its stationary track below,
to which the just solidified ingot is transferred
from that shown on Figure 38, as soon as solidifi- 20
cation has occurred, the cooling thenceforth oc-
curring without concomitant rotation, except that
the wheel of Figure 40 slightly rotates each mould
as it advances between index positions, and op-
erating stations. 25

Figure 41 is a vertical section taken on line
XLI—XLI of Figure 40, with the arrows.

Figure 42 shows in plan-view a complete cen-
trifugal casting unit, with furnace and mill as-
sembly, for use with the alternative type of cast- 30
ing-wheel shown on Figure 38 and succeeding
figures.

As the various transfer-arms for handling the
ingots between the casting-wheel stages, and
into and out of furnaces, form no part of the 35
present invention directly, except as they go to
make up a complete assembly, operative as a
whole, such transfers are not shown in detail
herein, reference being made to my co-pending
application on Ingot transfer arms, Serial 40
#680,967, filed July 18th, 1933.

In Figures 1, 26, 38, and 40 it was not con-
sidered necessary to show every ingot mould in
place and complete in detail, it being understood
that all intermediate stations are occupied by 45
moulds complete in every detail, as indicated at
one or more positions on each figure.

Directions of motion are indicated by arrows
throughout the various figures, forward and re-
turn motions being indicated by solid and broken 50
arrows side by side, respectively.

In all the figures, indentical parts are indi-
cated always by the same part numbers.

Referring now more particularly to Figure 1,
a well braced indexing-wheel is indicated at 1, 55
centred for rotation on the heavy king-pin 2,
suitably bolted to base below, and providing
means for the step-by-step advance of a mul-
tiplicity of ring-ingot moulds 3, held fore-and-
aft between rollers 4 and 5, and each provided 60
with a grooved ring 6, and flat ring 7 to run on
tracks 8, 9 below, as per Figure 1A, these tracks
being in turn mounted upon the heavy plate disc
10, provided underneath with the large diameter
driving gear 11, and also mounted upon the 65
king-pin 2, and carried by wheels which will
be later enumerated, upon the single stationary
track 12, shown on the stationary base 13 of Fig-
ure 1B. Again referring to Figure 1 a pouring
station is indicated at 14, solidifying stations next 70
to the left at 15, an adjustable hot-brushing sta-
tion at 16, mounted for angular adjustment as
required upon the circular track 17, extending
along the cooling stations 18, to and through the
similarly adjustable hot-trimming station 19, be- 75

yond which is the step-by-step indexing station 20, followed by the stripping station 21, and a plurality of mould inspection stations 22, before again reaching the pouring position. An 5 ingot-car track is shown at 23, adjoining the stripping station 21.

Turning to Figure 2, new parts not previously identified appear at base of king-pin 2 where the heavy mounting base 24 is bolted to foundation 13, at 25 which is a long bushing carrying wheel 1 through the ultra heavy roller bearings 26, well spaced apart vertically, the upper of which helps to stabilize the large diameter indexing-wheel 1, by means of a plurality of rods 10 15 27, passing through the turnbuckles 28, attached substantially as shown to parts 1 and 25 respectively. Lower rotating wheel 10 is mounted at its hub upon the ultra heavy roller bearings 29, serving to centre the rotating element, while its 20 weight, as well as that of the rotating ingot moulds 3, is carried by a plurality of heavy wheels 30 of high-grade alloy steel, mounted via heavy roller-bearings upon the cross-I-beams 31, midway between points of attachment thereof to 25 the rib-beams 32, of wheel 10, so that such wheels 30 will have some measure of elasticity in their mounting, to readily absorb the repeated shocks of the jarring of the moulds, the means for accomplishing which will be described later. 30 A suitable driving motor, preferably of the variable speed type, is shown at 33, meshing via the usual spur-pinion with gear 11, while a raised retaining wall is indicated at 34, to protect motor from any chance of contact with spilled hot 35 metal, a safety trough for the reception of which is further provided at 35, this being normally divided into short sections by suitable brick partitions so as to break up any spilled metal masses into short sections. The normal floor-level of 40 casting-room is indicated at 36.

In Figures 3 and 4, we find the ingot-stripping pin 37, the flange 38 on mould, the webbing of steel plate 39, suitable cross-bracing rods 40, the cross-stiffener bar 41, and the indexing teeth 45 42, in addition to parts already enumerated.

In Figures 5 to 10, inclusive, there are noted in connection with the pouring station 14, new parts not previously identified, consisting of the large stationary ladle 43, mounted on heavy trunnions 44, carried by the supporting block 45, and provided with the customary worm-wheel for angular adjustment of the pour (not shown), all supported by the piers 46, on the scale platform 47, mounted within the pit 48, and connecting through a series of knife-edge supported scale-levers 49, eventually leading to the downward pull rod 50, applied to one end of the compound scale-beam 51, bearing the large pointer weight 52 on one arm, and the smaller pointer weight 53 on the other arm, the throw of 53 being limited by the adjustable stop 54, while the customary assorted weights 55 are provided for preliminary rough adjustment to the weight of ladle and its burden.

65 A carbon or graphite valve for the hot metal is indicated at 56, liftable by the slide-rod 57, or other convenient means, a second valve and lift-rod being indicated in tandem to the first, for safety. Both are readily replaceable when 70 ladle is emptied. The hand levers for operating 57 will be of customary type, (not shown).

The hot metal stream enters the beveled open small end 58, of the cast-iron pouring cone 59, containing the heavy ribs 60 adapted to aid in 75 accelerating the incoming metal, without ma-

terial splash, before it enters the mould 3 as a thin sheet running at about the velocity of rotation of the mould, so as to avoid material spattering during the fill. Cone 59 is rotatably carried by the rollers 61, in turn rotatably mounted within the two housings 62 of slightly different diameters, carried by base 63, slidably mounted upon the rails 64, on which it may be shifted by the eccentrics 65, on the $\frac{1}{2}$ turn shaft 66, driven through appropriate reduction gearing as 10 shown, by the motor 67, with suitable limit switches of usual type to determine the half-revolution motions of 66, required to enter the safety guard-housing 68, over projecting rim 69 of mould 3, and avoid any possible throwing out 15 of molten metal during the pouring, 68 being made split to permit ready removal of any waste metal, should spillages occur. Suitable spillage protection plates will be provided under entrance to cone. 20

A suitable shoulder on cone 59 supports the spur-gear 70, appropriately keyed thereto, driven by pinion 71, keyed on shaft 72, shown underneath the pouring opening in Figure 7, for clearness, but in reality well to one side thereof, as 25 better indicated in Figure 5 above, this shaft being geared through the mitre pinion 73, 74, to shaft 75, driven by motor 76, mounted upon extension 77 of the sliding base 63. Or motor 76 may be turned at right angles from position 30 shown, and cone 59 driven direct by chain therefrom, if preferred, in order to obviate the use of mitre gears. Mould 3 carries at its left end a non-circular and gradually spiralled cam surface 78, engaging, when desired, with a lifting 35 roll 79, rotatably mounted directly underneath, at certain of the index stations, and more fully described in connection with a later figure. At the pouring station, suitable provision would of course be made for protection of operators and 40 all moving parts from any possible leakage metal, in line with usual practice here.

In Figures 11 through 14, inclusive, showing a white-hot-metal ingot internal brushing station, as per number 16 of Figure 1, there are found new parts 45 including the very stiff, heavy wire brush 80, with its hub mounted upon shaft of variable speed motor 81, bolted directly upon projecting arm 82, enterable within the hot ring-ingot 83, and in turn bolted to the slide 84, carried upon sliding-base 85 50 provided with the vertical adjustment bolts V. A., said slide 84 carrying the crank-arm 86, keyed to heavy shaft 87, mounted within the bearing-blocks 88, and driven through the worm-wheel or gear reductions 89, by the motor 90. 55

Crank-arm 86 is provided with a series of pin-holes 91, determining the throw, and through one of which the connecting rod 92 is rotatably pinned thereto, the other end of this connecting-rod being pivotally mounted upon appropriate 60 pin in the bracket 93, bolted solidly to base 85, arm 86 being equipped with the usual limit switches, (not shown), to determine half-revolution motion, under inter-lock control, whereby entrance into interior of ingot is prevented until mould 3 comes to a standstill in its progression, although under full rotation still, about its axis, said interlocks being similar in type to the one shown on the left in Figure 26, to follow, and so connected that brush must be retracted again completely 70 out of ingot, before wheel 1 can be progressed further by the motor of Figure 26, all this by means well known in the art, and therefore not shown on present drawings.

In Figures 15 through 25, I have shown a hot- 75

ingot trimmer mechanism 19, also insertable within, and retractable from a yellow-hot ring-ingot, under appropriate interlock control similar to that just mentioned, to prevent interferences between moving parts, and in which figures the circular trimmer-blades are indicated at 94, mounted on shafts 95, carried in the adjustable eccentric bushings 96, each capable of angular movement for adjusting purposes within the housing 97, by means of a worm-wheel at one end, engaging with the worm 98, on same shaft with the spiral gear 99.

- In order to pretty well balance the trimming thrusts transmitted back to frame, three of the above cutting blades 94, and associated parts down to 99, have been shown in my preferred trimmer construction, and angularly spaced about a common adjusting gear 100, as particularly brought out in Figure 19, on this sheet.
- As per Figure 16, this central gear 100 is shown mounted upon the hollow shaft 101, attached at its left end to the enlarged portion 102, both rotatable within the large hollow shaft 103, with 102 slidable over the special hollow shaft 104, rotatable therewith, in the thrust ball-bearing 105 at left, which is mounted at centre of housing 106, within which the shaft-housing 107 makes a sliding fit, under the operation of long rack 108 attached thereto, meshing with pinion 109, keyed to shaft 110, which, as shown in Figure 21, is driven by worm-wheel 111, and worm 112, on shaft of motor 113. Reverting to Figure 16, the heavy projecting shaft 103 is indicated as mounted in the heavy thrust and radial, ball or roller bearing 114, and in the heavy radial type roller-bearing 115, the end of 103 being bolted solidly to the cutter housing casting 97, before mentioned, while back of bearing 115, shaft 103 is keyed to the large herringbone gear 116, meshing with pinion 117, on shaft of motor 118, of the variable speed type, and mounted upon a flat in the shaft-housing 107, to which it is bolted. The relative cross-sectional shapes of housings 106 and 107 at the herringbone gear position is indicated by Figure 20, while Figures 21 and 22 show the conditions further to left.

Figure 23, which is simply an enlargement of the parts shown near the XXII—XXII section line of Figure 16, shows to better advantage how special shaft 104 is longitudinally drilled at 119, and provided with a longitudinal full length spline key-way 120 on one side, and a continuous spiral key-way 121; a shoulder-key 122, fitted in the screwed cap 123, being slidably fitted in 120, while a spiral hardened steel key 124 is set in the cap 125, screwed and locked into place on the left side of thrust shoulder 126, on end of hollow-shaft 102, this spiral key being made an easy sliding fit in 121, and over 104. Caps 123 and 125 will be locked in place by customary means, as by longitudinally drilled bolt-type keys. (not shown).

It will be self-evident that normal plain rotation of shafts 102, 103, and 104 together, produces no relative motion of 102, but that any sliding of 103 and its attached cutter-head 97 longitudinally, as by means of the rack 108, and pinion 109, will result in a slight rotational movement of shaft 102, and with it the spiral or other gear 100 at right, whereby the series of gears and worms 99, 98, and the eccentric bushings 96 will be rotated somewhat, radially shifting the cutter-blades 94, with respect to the axis of rotation of shaft 103, this shift being made just equal to the required taper or draft of the inside bore of ingot, necessitated by the outside draft, incor-

porated to greatly facilitate the subsequent stripping of the ingot.

It will also be obvious that other means might be devised for accomplishing in effect this taper cutting, or that ingot stripping means might be designed which would require no taper to the ingot, thus greatly simplifying the cutter mechanism under present discussion, so that I do not wish to preclude the inclusion of such simplified trimmer mechanism, although I have shown one 10 preferred construction only.

It will be observed that the drilled opening in shaft 104 connects at left, through the slip-joint coupling 127, with a suitable source of air under pressure, which is thence transmitted through shafts 101 and 102, the interior of closed cutter-housing 97, and the bent tubes 128, indicated at right end of Figure 16, to a point close to the cutting edge of cutters 94, so as to aid in the ejection from the mould of the borings produced, and prevent their getting imbedded in the face of the work by the further motion of cutter.

If desired, a tube may be run through centre of bore 104, to supply cooling water to blades.

Note that these cutter-blades 94 are set at an angle to the line of rotational travel of the work 83, so that the cutters are self-rotating, the ball-bearings provided for the latter being of a type that will take thrust as well as heavy radial loads, as well known in the art. The function of the large motor 118 is, therefore, not to propel the cutters against the face of the work and against the travel of the latter, but with the direction of travel of the work, at a speed somewhat less than the latter is moving under the urge of the centrifugal casting-wheel motor 33, and thus bringing the cutting velocity of the circular cutting blades down to a reasonable value for such an operation, although it is possible that further experience with this machine might indicate that motor 118 might be dispensed with, and I do not wish to preclude the use of such a simplified construction of trimmer.

Suitable rails 17, of same gauge spacing as those used for hot-brushing rig 16, permit the peripheral adjustment of hot-trimmer station 19 around wheel 1, as required.

Referring now to Figures 15 to 18, inclusive, freely rotatable pressure wheels 129 are shown in these four figures, being mounted upon heavy shafts 130, in appropriate anti-friction bearings, preferably of roller type, in the bearing-blocks 131, projecting downward from the cross-arm 132, having the long side extension arms 133 attached thereto, and mounted rotatably upon the common dead shaft 134, extending through upright wings 135, attached to the general base housing 106, which wings 135 also carry the worm-wheel 136, and its driving motor 137, operating through worm 138, and functioning the heavy screw-down mechanism 139, attached by suitable thrust collar to the cross-arm 132, and all operable to apply pressure to grooved ring 6, of mould 3, to steady the latter during trimming, and to develop greater rotating traction upon the driven rail 8 below, during this operation.

Possibly this supplementary mechanism might be dispensed with, however, although I have deemed it advisable to show it in my preferred construction of parts. It is even possible that hot-brushing station 16 might in some cases be found sufficient to put the hot ring casting in proper condition for subsequent use, without utilizing hot-trim station 19 at all, and such a dis-

position is included within the scope of the present invention, and the appended claims.

Figures 24 and 25 supplement Figures 23, and are self-explanatory, when taken in connection with the explanation given of the latter.

Referring now to Figure 26, one or any plurality of moulds 3, up to the capacity of wheel 1, is to be advanced step-by-step through one angular space 140 at a time, by the indexing mechanism 20, comprising the ultra-heavy link-chain 141, adapted to fit over the projecting teeth 42, of wheel 1, and carried around the idler-sprocket 143, and the similar heavy driven-sprocket 144, driven by the appropriate reduction gearing 145, operated through suitable worm or equivalent pinion on motor 146, preferably of the variable-speed, shunt-wound, direct-current type, whose shunt winding is indicated at 147, on the annexed wiring diagram, and connected through the large resistance 148, and the lead 149, directly to the two supply lines 150 and 151, provision for short-circuiting said resistance 148 being supplied by the heavy contact-points 152, one of which connects via conductor 153 to one end of the resistance mentioned, while the other contact-point connects through the swivel-arm 154, pivotally mounted upon the support 155, and thence through the lead 156 to remaining end of resistance 148. Swivel-arm 154 carries the freely rotatable rollers 157, 158, and 159, all preferably of Bakelite or similar highly-insulating material, the latter of which fits the two side-by-side depressions in the bent spring 160, used to retain arm 154 positively in either of its two throw positions, determined by contact of rolls 157 and 158, successively, with the projecting teeth 42, of wheel 1.

Conductors 149 and 156 also supply through support 155, the necessary current for contacts 161, of the normally closed type, carried by the swivel-arm 162, held in closed position by the spring 163, the outer contact of 161 being connected via lead 164, to the shunt coil 165 of heavy contactor 166, which functions in the direction indicated by small arrow, and against the action of suitable return-spring, (not shown), to close the heavy contacts 161, determining current flow through armature circuit of motor 146, and the series connected electric-brake release coil 168, of spring-gripped brake 169.

Coil 165 being connected through lead 170 to supply line 150, it will be noted that it receives current except when arm 162 is depressed, by contact of its roll 171 with a tooth 42 on wheel 1, which results in opening contacts 161, and 167, and the stopping of motor 146 instantaneously, the speed of latter having just before been reduced to about $\frac{1}{4}$ normal value by the depression of roller 158 by the tooth 42 next following, and thus short-circuiting the large resistance 148, in shunt-field circuit of motor 146.

Wheel 1 stops with arm 162 held depressed, and with next succeeding tooth 42 lying just midway between rolls 157 and 158, of arm 154, roll 158 being down, as just previously noted. Motor 146 can not again start up, until operator closes switch 172 momentarily, energizing coil 165 through the connection 173, starting up said motor slowly and moving the tooth 42 away from contact with roll 171, so that contact 161 closes, maintaining the circuit through coil 165 after appropriate spring-return (not shown) on switch 172, has opened up the latter. A moment later, the next succeeding tooth 42, on wheel 1, which had stopped between rolls 157 and 158, reaches

roll 157 and depresses it, as is shown in this figure, throwing over arm 154 to its open-contact position, inserting the resistance 148 into shunt-field coil circuit 141, and speeding up the motor 146 to normal running value, where it remains until next succeeding tooth 42 hits roll 158, closes contacts 152 again, short-circuiting resistance 148, slowing down motor 146, after which roll 171 again contacts with a tooth 42, and the wheel 1 stops promptly, supplementary electric brakes to assure this being added, if required, (but not shown).

Other means for accomplishing the above sequence of operations will be obvious.

It will be observed that wheel 1 simply advances the moulds 3 step-by-step, but has nothing to do with their rotation on their own axes, which is done by motor 33.

Turning now to Figures 27A and 27B, which, being in much larger scale, than heretofore, show to better advantage one preferred form of casting mould 3, it will be noted that former figure refers to a mould for casting somewhat tapered or coned ring-ingots, while the latter figure covers a mould for ingot with parallel faces.

In spite of the greater difficulty of its centrifugal production, the tapered form of ingot is believed to be preferable, because of decreased stripping difficulties encountered in that case. Since for proper rolling, the thickness of ingot wall 30 should, if anything, be proportionately thicker on the smaller diameter end of ingot, it is found that the production of tapered ingots points to the mounting of entire casting wheel 1 and associated rotating disc 10, on a slight angle downward from the pouring position. This is not shown on drawings, but is believed to be entirely within limits of practical construction and hence advisable.

In these two figures, I have indicated my preferred mould 3 as having a high-tensile steel plate shell with spaced peripheral ribs 174 slightly projecting therefrom, as at the multiplicity of points indicated, while more or less similar, but outwardly projecting, and intermediately positioned ribs 175 are placed upon the exterior of cast-iron ingot-mould proper 176, on the interior of which an ingot 33 is shown in casting position, while between ribs 174 and 175, I have placed a great multiplicity of steel rods 177, to give powerful support to mould proper 176, but a little elasticity to accommodate some thermal expansion therein, without breakage.

This part of the construction is perhaps better indicated in Figure 36 following, where a section transverse to axis is shown. It will be noted that all these construction items greatly limit the opportunities for heat transfer from mould proper to the outer steel plate shell, and that ring 6 is also in contact with shell 3 over very limited areas only, preventing any very pronounced over-cooling at the position of the rail 8, all this with the idea of getting the maximum possible amount of temperature uniformity in the ingot as it leaves the mould, and thereby greatly reducing the time required later on in the soaking-pit, or temperature equalizing furnace, or other heating means utilized before rolling.

Reverting to Figures 27A and 27B, these grooves under ring 6, are shown at 178, the welded-on, or otherwise attached ribbed-rim of mould at 69, and the shaker cam-face at 78, the latter being profiled around the perimeter as desired, for either one, or a plurality of drops by mould, per revolution. A spring retaining-ring 179, having

- a split at one portion of its periphery, is shown at 179, with a multiple retaining ring of thin steel strips 180 to make direct contact with the hot ingot, and thus avoid much heat loss here.
- 5 Two or three of these thin rings will undoubtedly be lost with each pouring, but the multiplicity of layers and many thin films present should lead to low heat transfer at this point, thus holding up the ingot temperature at one of its vital points.
- 10 Similar rings 181 are placed at opposite ends of the casting, against the ingot-stripper piston 182, located just inside the mould head 183, mounted solidly on shell 3, by means of the flanged and welded-on ring 184, attached to head 183 by the slot-bolts 185, and the outwardly driven wedges 186, or equivalent means. Stripper piston 182 is threaded upon, or otherwise solidly attached to the stripping-pin 37, slidingly mounted within flange 38, and the turned neck 187 provided for the tracking of rolls 5, heretofore shown.

It is again noted, however, that the preferred form of piston 182, and of head 183, will be as indicated in Figures 11 and 12, so as to be able to accommodate such a brushing-rig, if desired. In ejection of the ingot, 37 and 182 will be moved over to the left, more or less toward the dotted line position 37'-182', usually far less than the amount indicated here, however, especially if 30 tapered ingot is used.

Referring now to Figures 28 to 33, inclusive, covering ingot-stripper 21, new parts comprise the bent supporting columns 188, so mounted as to entirely clear the emergent ingot, and welded 35 to the webbing of steel plate 189, carrying the stripper-housing and gear casing 190, provided with the strong projecting arms 191, adapted to engage back face of mould stripper-flange 38, but well beveled as required, at points of entrance thereupon, and arranged to normally clear the latter by $\frac{1}{2}$ " or more, except during the actual stripping process.

Mounted upon above housing 190, is the variable speed motor 192, preferably of the series type, so as to be capable of tremendous momentary torques, and driving through the appropriate heavy reduction-gear train 193, the large, roller-bearing mounted, combined gear and thrust-nut 194, mounted upon the coarse thread thrust-screw 195, carrying at its left end the heavy, horizontally guided, non-rotating fork 196, arranged for very easy entrance over head of stripper-pin 37, of each successive mould 3, appropriate edges of fork 196 being well beveled to promote such entrance, with a normal clearance all around of possibly $\frac{1}{2}$ ", when not in actual stripping operation. In some cases the mould 3 will be lifted clear of the rails 8 and 9, and stopped from rotation, by apparatus extraneous to the present application, but as roughly indicated in outline in Figure 42, following, before the stripping operation is encountered, and the stripper-arms 191, and fork 196, are here shown for that type of operation. But in other cases, as was indicated, 60 for example, in Figures 1 and 34, it may be desired to leave the mould in full rotation clear up to and through the stripping, in which case the head of stripper-pin 37, and the back face of flange 38 must engage the respective stripper parts 196 and 191 through appropriate roller or ball thrust-bearings, of which that on 196 will be of standard type, and the others special, but since these elements do not enter into my present claims, they are not elaborated upon further here.

75 Or screw 195 and head 196 may in this case be

made to rotate with the mould, at the same velocity of rotation, and out of a stationary nut, thus avoiding thrust bearing complications, if preferred. In either case, screw 195 is operated to the left until stripper piston 182 is carried 5 sufficiently far to "start" the ingot, and bring it in contact with the power-driven, angularly positioned feed rolls 197, which are well beveled off on the ingot entering side, to make sure that ingot will ride up on them readily, these rolls 10 being purposely set just a little above projected line of interior surface of mould, in order to very slightly urge the ingot up with each half revolution thereof, and thus cause it to "work" itself loose positively at the opposite end, while the 15 rolls 197 and 198 give it a constant urge to work over to the left, and eventually onto the receiving rolls 199, mounted upon suitable base 200, and against the stop 201 at the left, which is easily positioned as required, but difficult to show, 20 due to space limitations on the sheet.

Feed-rolls 197 and 198 are driven through appropriate bevel-gearing 202, by the shaft 203, carried upon suitable bearing-blocks, and driven, either directly or through appropriate reduction- 25 gearing, by the preferably series-type direct-current motor 204, suitably carried by bracket from column 188, of the frame, as shown.

It will be noted from Figure 30 that shaft 203 is set with a considerable downward slope toward 30 removal side of ingot, to allow left hand rolls 197, 193, and also 199 to be low, and thus permit wheel 1 to be advanced in case any ingot should stick in the mould, or after partial ejection therefrom.

If mould is non-rotating during stripping, rolls 197, 198, and 199 may be co-axial with mould.

All parts of the stripper, including the columns 188, are designed with this "sticking" contingency in mind, so as to not hold up the casting process, 40 the stuck ingot and mould being simply carried on for one or two steps further around wheel 1, and then lifted off bodily, by crane, for further attention on the floor, while a spare mould is inserted in their place in wheel 1, without a moment's hesitation in the regular casting procedure elsewhere having occurred. For similar reasons, the rolls 199 are put on a slope also, these rolls, which may sometimes be power-driven also, if desired, being used to carry the ring-ingot 83 50 after it has been withdrawn from mould to its 83' position, ready for the entrance therein under of the ingot-support arms 205, and ingot-lift arms 206, of ingot-carriage 207, indicated in Figures 28, 29, and 31, in broken outline. On raising lift 55 arms 206 to their top, or 206' position, ingot 83' is carried up to 83", as shown in dotted outline, in Figure 31, where it clears the rolls 199, and carriage 207 is ready to depart. If desired, rolls 199, and their base 200, may now be depressed, by 60 any suitable lifting and lowering means, such as the hydraulic plunger 200a shown, to permit ingot-carriage to leave in either direction required, along track 23.

Reverting to Figure 29 for a moment, I have 65 shown on the right a normally closed set of contacts 208, for connection in series with shunt-coil on one throw of the double-throw contactor (not shown), supplying motor 192, said contacts 208 being opened up by contact with right-hand 70 end of screw 195 on its return, to prevent overrunning of the latter, with consequent jamming. As the left-hand motion of screw 195 is under the control of an entirely separate shunt-coil on the other throw of contactor, the opening of 208 75

does not prevent motion of said screw to the left, however, as soon as may be required thereafter, and if desired, such travel to left may be similarly protected by a similar set of limit contacts (not shown).

5 It is believed that Figures 32 and 33 require no comment, being self-explanatory.

Referring now to Figure 34, it is thought that the general scheme of operations here indicated, 10 will also be self-evident to anyone skilled in the art to which it appertains, so that in view of the rather extended exposition up to this point, only such comments as appear necessary to a full understanding of the case will be injected. Hot 15 metal being available, and wheel 1 brought up to position ready for the next pour, with disc 10 under full rotation, stop 54, of Figure 6, will be set and locked at the ingot weight desired, index- 20 weight 53 shoved over against it, and scale weights 55 and 62 adjusted to just balance the ladle 43 and its burden of metal, after which weight 53 is thrown clear to the right and left there, as shown, and motor 76, of Figure 5, is used to bring pouring-cone 59 up to speed, while motor 67 is 25 functioned far enough to throw said cone to its extreme right position, as shown in Figure 7, and stopped there, following which rod 57, and its attached valve 58, are lifted to start the pour, this latter being continued until balance lever 51, of 30 Figure 6, begins to rise, thus indicating that precisely the proper amount of molten metal by weight, has been poured off, when 58 is instantly closed by means of rod 57, operated by hand, motor, or other convenient means located upon the 35 scale platform, so as not to affect the weighing operation. Motor 67 is now functioned to carry shaft 66 through another $\frac{1}{2}$ revolution, and stopped, after which wheel 1 is indexed around one step, by the proper functioning of parts at 40 station 20, as shown in Figure 26, bringing a new mould into position for a pour, which is proceeded with after a new re-weighing is accomplished, just as before.

Brushing station 16, as more particularly shown 45 in Figures 11 and 12, having been set a sufficient distance angularly around the wheel 1, to allow for solidification of the ingot, and exactly at an index stop position, this powerful wire brush 80, running at full motor speed, is run slowly into and then back out of the ingot 83, while a new pour 50 is under way, and so as to be in the clear before such pour is completed. A little further around the wheel 1, the hot-trimmer 19, as per Figure 16, is similarly run in and then out again, over 55 the somewhat cooler, but still bright hot metal, provided such added trimming is necessary for the work under way.

Eventually the stripper station 21, as per Figures 28 and 29, is reached, and ingot 83 ejected 60 onto rolls 199, ready for entry of ingot-carriage 207, by which it is usually delivered either to one of the heating furnaces 209 or 210, via transfer-arm 211 shown, or to ingot storage tracks 212, 65 via the cross-transfer table 213, and, if desired, the same car 207 may be used to deliver the ingots from furnace to mill 214, after proper "soaking" period.

If white hot ingots can always be counted upon, 70 direct from the casting wheel, then one heat-equalizing furnace might be sufficient, but usually provision has to be made for taking an occasional ingot out of the storage pile, and therefore cold, and thus requiring more heating to prepare for 75 rolling, so that the two stage furnace meets the

requirement of a steady flow of hot ingots to mill, to better advantage.

As indicated by the break line 215, the usual distance from furnace to mill had to be fore-shortened in this figure. Straight ingots, or cut 5 slabs, enter the mill 214 via entering live-roll table 216, and the straight ingot-car track 23', using same ingot-carriage 207 as before. Ladle 43 is brought over from the open-hearth, or other furnaces 217 by usual hot-metal crane, (not 10 shown).

Referring now to Figures 35 to 37, inclusive, the means 78, 79, for accomplishing the "jarring" of the ingot, concomitantly with the centrifugal casting and solidification thereof, can be 15 better shown than in Figure 7, where other things were under particular discussion, it being understood, however, that the cam surface 78, shown with a single rise and fall per revolution, may include a multiplicity thereof in some cases, if so 20 desired. In these figures, the demountable, hard alloy-steel ring 79, is carried upon the very heavy and freely rotatable shaft 218, mounted upon the very heavy roller bearing 219, and the somewhat lighter similar bearing 220, in turn mounted 25 within the heavy eccentric bushing 221, rotatably mounted within the steel housing 222, and capable of angular adjustment therein, by means of the heavy spur gear 223, keyed to bushing 221, and mounted concentric with outer face 30 of latter, this gear being driven by pinion 224, mounted upon and keyed to same shaft as worm-wheel 225, in turn functionable by an appropriate worm, on shaft of suitable motor 226, or other equivalent operative means. One of these mould 35 lifting rigs will be placed on mid-line of each of the first 8 or 10 steps of wheel 1, out of the casting position, and including the latter, each being so mounted as to be rotated by the flange 78 constituting the lifting cam of the successive moulds 40 83, but at such a height that when fully raised, as is shown in Figure 36, the lesser radius elements of cam will clear the wheel 79 by $\frac{1}{8}$ " or so, so that the impact of the fall will be taken by the heavy track 8, on disc 10, and not by the less 45 sturdy bearings 218 and 220, not so well adapted to take the continual hammering. At points reached after solidification of ingot has occurred, and where no further "shaking" of the latter is necessary, or desired, all the eccentrics 221 may 50 be lowered to down position, so that wheel 79 entirely clears all parts of the cam surface 78, and therefore no further jarring occurs.

The centrifugal action alone tends to separate 55 out all low weight inclusions within the mass of the casting, but this action is greatly accelerated by the jarring, particularly in so far as gaseous inclusions are concerned, which are easily trapped by the more or less viscous metal as it begins to 60 solidify, unless jarring occurs.

The combined centrifugal and jarring effects 65 give ingots of remarkable solidity and purity, and freedom from the usual inclusions and fissures, particularly after the internal cleaning off operations that I have provided for, for removal of 70 surface dross, brought to the inside of ingot by the centrifugal action.

Referring now to Figures 38, 38A, 38B, and 39 75 I have here shown an alternative form of simplified casting unit in which rotation of the ingot 70 is not maintained except during the actual period of solidification, or slightly beyond this point, so as to include the hot-brushing operation, which is preferably accomplished while the metal is extremely hot and soft, to some extent. In this 75

disposition, the ingot mould, as soon as convenient after solidification of its burden, is picked up bodily from the wheel 1', while still in rotation, by an appropriate transfer-arm, (not shown), slowed down to zero rotational speed and its energy passed on to another mould which is being speeded up on opposite end of the transfer arm at the same time, the latter being then put into the just vacated position in wheel 1'. 5 while the slowed down mould is deposited on vacated position in wheel 1' to be described under Figure 40, where subsequent operations are carried out without further rapid rotation. The above transfer arm is not described further in detail here, being merely shown positioned at proper point in the later Figure 42, to complete the presentation. 10

With this explanation, it is believed that no further description of Figures 38, through 39, is called for, except that I have here shown one new part, the gas or other type of heaters 227, appropriately mounted by any convenient means, (not shown), at or close to the mid-line of the successive step positions of wheel 1', so as 15 to retard the solidification of interior face of the ingot as required, to promote solidification on a radial inward direction only, throughout the mass of the ingot. 20

I intend that such heating means may be applied to the early steps after the pouring in Figure 1 also, if so desired. In Figures 38 to 42, inclusive, parts which are very similar to, but not identical with, those previously shown, will be identified by the same part numbers, but with a prime (') added, to distinguish. 25

Referring now to Figures 40 and 41, substantially the only changes from the disclosure of Figures 1 to 4 inclusive, are those of material reduction of over-all diameter of the wheel element 1'', (the 1' having been already appropriated for Figures 38 and 39), and the entire elimination of the rotating-disc element 10 of the earlier figures mentioned, with all the propelling parts and tracks therefor, the single stationary track 12, of Figure 1b, being replaced in Figures 40 and 41 by the two tracks 12', on which, in this case, the moulds 8 roll directly, as they slowly progress around the successive stations of wheel 1''. 30

Turning to Figure 42, the general mill assembly of my alternative casting unit, and associated parts, is shown, along with necessary heat-equalizing furnaces, and the mill proper, substantially the only new element shown, aside from minor track re-locations, as compared with Figure 34, being the two-stage casting unit previously mentioned, consisting of parts 1' and 1'', and the special transfer-arm 228, not shown in detail on any of the drawings, but previously referred to in the text. 35

With the exception of operation changes introduced by the sub-division of the original wheel 1 into the two parts 1' and 1'', and the necessary introduction of the action of special transfer arm 228 just mentioned, the general functioning of all the elements of the entire assembly will be substantially as before outlined in connection with Figure 34, and so need not be repeated. 40

In connection with the use of the ingot casting equipment of my invention, certain very definite advantages accrue from the combination of the centrifugal and the jarring actions, heretofore not combined in a single machine. Every possible improvement in the quality and soundness of the ingot, leads directly to lowered scrap losses 45

and plate rejections in the mill, which are of vital importance in cutting down the conversion costs from ingot to sheet. 5

Since the large volumes of gases that are given off from a solidifying ingot, are not driven off from it instantaneously, but more or less progressively as the temperature falls and the metal begins to get very viscous, much of such gas is trapped within the ingot, even in the case of centrifugal casting, unless decided "jarring" is 10 introduced at just the critical period as solidification approaches. 15

This frees the entrapped gaseous elements better than any other known means, while it also slightly assists the centrifugal forces in further 15 than normal separation of light non-metallic bodies present in the cast metal, thus tending toward a more uniform metal in the ingot itself. 20

Other very definite advantages accrue from my provision for solidification on a radially-inward 20 progressing single cylinder of solidification only, under the influence, in addition, of the centrifugal action, whereby internal piping is substantially eliminated, and an essentially solid ingot provided. 25

This action is assisted by internal heating of the ingot, to some extent, during the period of such solidification. 25

Further very definite advantages accrue from my provisions for cleaning off or trimming of the 30 interior wall of the ring-ingot while still very hot, so as to be very easily operated upon. 35

Other advantages accrue from my provision of means whereby the "jarring" action may be carried out through an adjustable fraction of the 35 whole freezing operation, and with adjustable intensities at the successive steps. 40

Still further advantages accrue from the elimination of the blooming mill, by the production of relatively wide and thin cast ingots, which may 40 be entered immediately into the final rolling mill. 45

Other advantages accrue from the production of such thin walled ingots that substantially the whole exterior surface of said ingot will be close 45 to the rolls in the very first pass through the mill, so that little "pulling apart" of metal not close to the rolls, has to occur, breaking open the dendritic crystals here. 50

The thin walled ingot also allows less time during solidification for the segregation of the different components of the metal mixture originally poured, so that greater than usual uniformity of composition results, throughout the mould. Yet other advantages accrue from my 55 combination for the first time, of all the above advantages and others, in a commercial product, by the means described. 55

While I have shown a convenient apparatus for producing ring-ingots of the highly compacted 60 type desired, other designs will be self-evident to anyone skilled in the art, and it will be understood that changes in the apparatus, or the operation of its parts, may be made without departing either from the spirit of my invention, or 65 the scope of my broader claims. 65

What I claim is:

1. In a ring-ingot centrifugal casting system, a rotatable mould, a power rotating means therefor, a molten-metal pouring means applicable to 70 fill said mould as far as required, and a mould jarring means applicable to said mould as required to jar the contained ingot concomitantly with the application of centrifugal force thereto. 75
2. In a metal ingot centrifugal casting system,

- a rotatable mould, a power rotating means applicable thereto, means for pouring molten metal into said mould, a mould jarring means applicable to said mould concomitantly with the pouring of said metal and the rotation of said mould, whereby the gas eliminating effects of centrifugal action and of jarring are made additive, and a power operable adjusting means applied to said jarring means and operative during said pouring and/or thereafter.
3. In a metal ingot centrifugal casting system, a plurality of rotatable moulds, power rotating means applicable thereto, means for pouring molten metal into said moulds successively, a guiding and spacing system applicable to all of said moulds concomitantly, step-by-step advance means of the power type and applicable to precisely advance said guiding and spacing system and said moulds substantially transverse to the axes of rotation of the latter, and a plurality of mould jarring devices positioned operatively at successive pause positions of said moulds so as to contact therewith successively as and when required.
4. In a ring-ingot casting system, a hollow ingot-mould, means to pour molten metal into said mould, a separately mounted power operable circular trimming tool, a slide for said tool, power means applicable over said slide to enter said tool substantially axially within said ring-ingot while still within the said mould, and to subsequently retract said tool to clear the same, and an adjusting means for said slide, allowing said tool to enter said ring-ingot along a slightly coned course, as and when required, and by an adjustable amount of slope toward axial line of mould.
5. In a ring-ingot centrifugal casting system, a rotatable hollow mould, means for rotating said mould axially thereof, a power-driven rotating-brush rig, step-by-step advancing means of the power-operated type and applied to said mould to advance the same substantially transversely to its axis, power-entering means applied to said rotating-brush rig to enter and retract the same axially within said mould during one of the pauses in the advance thereof, and a means for pouring a measured amount of molten metal into said mould at a preceding pause in said advance.
6. In an ingot centrifugal casting system, a rotatable mould provided with a circular track therearound for frictional drive purposes, an auxiliary cam track placed substantially parallel thereto and provided for use in jarring said mould and its contents, a mould contacting means cooperating with said cam track to provide said jarring, a stationary mounting means provided for said mould contacting means, a tangentially applied friction drive arranged to co-operate with said circular track, to rotate said mould, and a means for pouring molten metal into said mould.
7. In an ingot centrifugal casting system, a rotatable mould which is arranged to be freely movable vertically at all non-operating periods and without alteration of any parts, two circumferentially positioned and axially spaced friction-drive track elements therearound, a substantial-
- ly horizontal friction-drive disc mounted rotatably below said mould and contacting tangentially therewith under the full applied weight of said mould and its contents as the only traction producing elements, power rotating means applied to said discs to rotate it transversely to the axis of said mould and rotate the latter thereby, roller guides applied to the opposite horizontal sides of said mould to position it both transversely and longitudinally of its axis, mounting means for said guides, and means for pouring molten metal into said mould.
8. In a centrifugal casting system, a rotatable hollow mould, power means for axially rotating said mould, mould jarring means applicable during and after the pouring period, and concomitantly with the centrifugal action applied to said mould and its metal content, and a means for relieving the jarring means of the impacts producing said jarring.
9. In a centrifugal ingot casting system, a plurality of rotatable hollow moulds, power means for concomitantly rotating said moulds, power means for the concomitant step-by-step advance of said moulds substantially transverse to their respective axes, a plurality of mould jarring means applied thereto at successive pause positions in said advance, means for pouring molten metal into said moulds successively, and power means for selecting the sequence of the jarring stations and the total number to be made operative, as required.
10. In a metal ring-ingot centrifugal casting system, a multiplicity of hollow rotatable ingot moulds, means to rotate said moulds axially thereof, power means to advance said moulds step-by-step and substantially transverse to their respective axes, means to pour molten metal into said moulds in succession at the successive pauses in said advance, a circular-disc cutter type of ingot-trimming tool positioned at one of the pause positions of the said moulds and subsequent to the pouring position thereof, power means for rotating said cutter, and further power means for entering and retracting the same axially within said ingot.
11. A metal ring-ingot centrifugal casting system according to claim 10, wherein the means for entering and retracting the said circular-disc cutter within the ingot is characterized by the provision of co-operating adjustment means effective to advance said cutter in a near-axial direction along the interior surface line of a somewhat coned ingot.
12. A metal ring-ingot centrifugal casting system according to claim 10, wherein there is provided a mounting track for said ingot-trimming tool, which track extends substantially in the direction of step-by-step advance of said moulds and through several of the pause positions thereof, thereby providing the means whereby said tool may be positioned at that pause position where the best operating temperature for hot trimming is found to obtain.

JAMES L. ADAMS, JR.
